UNITED STATES PATENT OFFICE.

PHILLIP A. SHAVER, OF PUENTE, CALIFORNIA.

DESIGN FOR A CHILD'S HIGH CHAIR.

Application filed July 25, 1927. Serial No. 22,876. Term of patent 7 years.

To all whom it may concern:

Be it known that I, PHILLIP A. SHAVER, a citizen of the United States residing at Puente, in the county of Los Angeles and State of California, have invented a new, original, and ornamental Design for a Child's High Chair, of which the following is a specification, reference being had to the accompanying drawing, forming a part thereof.

Figure 1 is a front elevation of the child's high chair, showing my new design.

Figure 2 is a rear elevation of the same, Figure 3 is a top plan view of the chair, Figure 4 is a side elevation of the chair, and Figure 5 is a top plan view of the chair with the tray removed.

I claim:

The ornamental design for a child's high chair, as shown.

PHILLIP A. SHAVER.
